UNITED STATES PATENT OFFICE.

JAMES F. McCLOSKEY, OF WOONSOCKET, RHODE ISLAND.

DESIGN FOR A GRAVE-MARKER.

48,562.

Specification for Design.

Patented Feb. 15, 1916.

Application filed October 22, 1914. Serial No. 868,137. Term of patent 14 years.

To all whom it may concern:

Be it known that I, JAMES F. McCLOSKEY, a citizen of the United States, residing at Woonsocket, in the county of Providence and State of Rhode Island, have invented a new, original, and ornamental Design for Grave-Markers, of which the following is a specification, reference being had to the accompanying drawing, forming part thereof.

Figure I represents the front view of a

grave marker of my design. Fig. II represents a side view.

I claim—

The ornamental design for a grave marker, as shown.

JAMES F. McCLOSKEY.
